(57) **CLAIM**

The ornamental design for a car pet mat, as shown and described.

DESCRIPTION

FIG. 1 is a top perspective view of a car pet mat showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a bottom perspective view thereof in an unfolded state;
FIG. 9 is a top perspective view thereof in an unfolded state;
FIG. 10 is an enlarged view of portion 10 in FIG. 1; and,
FIG. 11 is an enlarged view of portion 11 in FIG. 4.
The broken lines in the drawings illustrate portions of the car pet mat that form no part of the claimed design.

1 Claim, 11 Drawing Sheets
